UNITED STATES PATENT OFFICE.

HENRY H. LYON, OF RIVERSIDE, CALIFORNIA.

APPARATUS FOR AUTOMATICALLY LIGHTING SMUDGE-POTS.

SPECIFICATION forming part of Letters Patent No. 789,618, dated May 9, 1905.

Application filed November 21, 1903. Serial No. 182,164.

To all whom it may concern:

Be it known that I, HENRY H. LYON, a citizen of the United States, residing at Riverside, in the county of Riverside and State of California, have invented certain new and useful Improvements in Apparatus for Automatically Lighting Smudge-Pots; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in automatic smudge-lighting apparatus adapted to be used for igniting smudge-pots within the frost belt as a preventive from damage to orchards by the frost, and comprises the utilization of the Hertzian-wave principle for rendering a high-resistance wire incandescent, whereby the material forming the smudge may be ignited.

Within the frost belt in various sections of the country during cold weather it is customary to light fires in orchards for the purpose of preventing damage by frost, and for this purpose briquets or oil-pots or other devices are common which are lighted by hand. As it is a well-known fact that frost occurs early in the morning, it is a difficult matter to get persons out to ignite the smudge apparatus at the proper time. By the provision of my apparatus the smudge may be made automatically, the apparatus being set in operation by the use of a thermostat, which may be so adjusted as to operate at any degree of temperature, or, if preferred, an electrical switch apparatus may be employed, whereby an electric circuit may be closed for the purpose of causing the igniting-wires to be heated or rendered incandescent.

My invention consists, further, in various details of construction and in combinations and arrangements of parts, which will be hereinafter fully described and then specifically defined in the appended claims.

I illustrate my invention in the accompanying drawing, which, with the letters of reference marked thereon, forms a part of this ap-

plication, and in which drawing I have shown a diagrammatic view of my apparatus with parts in section.

Reference now being had to the details of the drawing by letter, A designates a thermostat carrying a contact-point, and C designates a metallic strip with which said pointer is adapted to contact to close the circuit. Said contact-point is connected by the wire D with the primary E of an induction-coil through the battery F, so that on closing the circuit a current is sent through the primary. A suitable switch G is provided whereby the circuit may be closed by use of the same, if desired, when the apparatus is actuated without the employment of the thermostat.

K designates the secondary of the induction-coil, both poles of which are connected to suitable terminals within the metallic reflector N through the wires N', which may be so arranged as to cause the Hertzian waves developed to fall upon a given area of ground. It is well known that the Hertzian wave can be reflected or refracted as ordinary light, and the purpose of this reflector is to control the waves so as not to effect the receivers in a neighboring orchard. The reflector may be erected at a suitable elevation in the orchard, while the transmitter may be located conveniently and may be inclosed in a suitable metallic casing. The receivers, of which there may be any number disposed in an orchard, each carries a coherer Q, which may be provided with an earth connection Q' and an air connection Q"; but owing to the fact that the waves would not have to travel any great distance these are not absolutely necessary.

The coherer is in circuit with a local battery R, while a portion of the connections S and S' is prolonged so as to include a short piece of wire of high resistance, preferably bent in the form of a loop, as at T, which is adapted to be brought to an incandescence by the local battery R when the circuit is completed through the coherer. Surrounding the metallic loop T is an inflammable substance L, preferably composed of glue, water, phosphorus, and potassium chlorate, although I do not limit myself to any particular substance; but the above materials properly mixed are suitable,

being hard, a non-conductor, and burns the proper length of time. This fuse L is to be suitably attached by pins to the briquets or floated on the surface of the oil J, held in the 5 receptacle J'. By any mechanical arrangement a resistance-wire without a covering of fuse may cause the ignition of the smudge, in which case it will be necessary to heat the wire to incandescence.

- 10 The operation of my apparatus is as follows: On completing the circuit through the primary of the transmitter as the pointer B comes in contact with the metallic strip C or when the switch G closes the circuit Hertzian waves 15 are developed within the reflector N and are caused to impinge upon the receivers within the area controlled by the reflector and by their action cause the circuit to be completed through the coherer, the battery R, and the 20 wire loop T. The current developed through the battery R raises the loop T to incandescence, thus firing the inflammable compound L, which in turn ignites the oil in the smudge pot or receptacle.
- 25 From the foregoing it will be observed that by the provision of an apparatus embodying the features of my invention a simple and practical apparatus is provided for automatically igniting smudges located over various 30 areas of space and which may be set to be actuated at any degree of temperature or by the manipulation of the thermostat for closing the circuit.

While I have shown and described an apparatus adapted especially for the transmission of the Hertzian waves for the purpose of lighting smudges, it will be understood that, if desired, I may utilize other means for electrical transmission in which resistance-wires are 35 utilized for the purpose of igniting the smudge-pots, and, if desired, I may make various alterations in the details of construction of the apparatus without in any way departing from the spirit of the invention.

40 Having thus described my invention, what I claim as new, and desire to secure by Letters Patent, is—

- 45 1. An automatic smudge-lighting apparatus comprising a coherer, high-resistance wires 50 electrically connected therewith, a source of electricity for heating said wires, and a Hertz-

ian-wave apparatus for reducing the resistance through said coherer, whereby the inflammable material in the smudge-pot may be ignited as the wires are heated, as set forth. 55

2. An automatic smudge-lighting apparatus comprising a coherer, a high-resistance wire connected therewith, a fuse adjacent to said resistance-wire, a Hertzian-wave apparatus for reducing the resistance through said co- 60 herer, as set forth.

3. An automatic smudge-lighting apparatus comprising a coherer, a high-resistance wire with circuit therewith through a battery, a fuse apparatus secured to said resistance-wire, 65 adapted to ignite the contents of the smudge-pot, a Hertzian-wave apparatus, a reflector therefor, as set forth.

4. An automatic smudge-lighting apparatus comprising a smudge-pot, a coherer with a 70 high-resistance wire and battery in circuit therewith, a fuse mounted upon said resistance-wire adapted to ignite the contents of said smudge-pot, a Hertzian-wave apparatus, a reflector to prevent the diffusion of the 75 Hertzian wave, a thermostat and electrical connections between said thermostat and the primary of the induction-coil of the apparatus, and adapted to close a circuit through the induction-coil at a given degree of temperature, as set forth.

5. An automatic smudge-lighting apparatus comprising a coherer, a high-resistance wire and battery connected therewith, a fuse mounted upon said wire adapted to ignite the contents of the smudge-pot, a Hertzian-wave apparatus with the primary and secondary of the induction-coil, a thermostat having a contact-point electrically connected with the primary of the induction-coil, an adjustable contact-point upon the thermostat against which the pointer is adapted to contact at a certain degree of temperature, and connections between said point and the winding of the primary induction-point, as set forth. 95

In testimony whereof I hereunto affix my signature in presence of two witnesses.

HENRY H. LYON.
